STRAP STRETCHING DEVICE

Frederick A. Endress, Chicago, Ill., assignor to
Acme Steel Company, Chicago, Ill., a corpora-
tion of Illinois

Application May 8, 1939, Serial No. 272,357

8 Claims. (Cl. 254—66)

This invention relates to improvements in strap stretching devices and its purpose is to provide improved means for drawing a binding strap taut around a box or package.

The invention is directed particularly to strap stretching devices of the pusher bar type in which a tubular seal, having one end of the strap threaded therethrough and reversely bent beneath it, is engaged by a plate or flange carried by one part of the tool, while the other end of the strap, which is passed around the package, extends through the seal and is held by a gripping device capable of relative movement with respect to the plate or flange which bears against the seal so that upon movement of the gripping device with respect to the plate or flange, the strap is drawn taut around the box or package. Strap stretching devices of this form are particularly adapted for use on boxes or packages having relatively small surface areas so that strap stretching devices having two relatively movable gripping devices engaging the opposite ends of the strap can not be readily employed because of the lack of space for accommodating the relatively movable gripping devices on the surface of the box or package. By employing the seal as a holding device for one end of the strap and causing one of the relatively movable parts of the strap stretching device to bear against the seal, it is possible to form a joint at one end of the tool and to reduce greatly the required space for the accommodation of the device on the surface of the package.

The principal difficulty with prior devices of this type has been that the plate or flange which has been provided to bear against the seal for holding one end of the strap during the stretching process, has been formed to extend between the overlapping strap ends and to bear against the opposite edges only of the seal, with the result that the pressure set up by the operation of drawing the strap taut has caused the edge of the plate or flange to shear opposite sides of the seal so that the usefulness of the seal has been greatly impaired or destroyed. This difficulty is overcome by the present invention which has for its principal object to provide means for engaging the tubular seal along one of its edges parallel to the plane of the strap so that a large bearing surface for the seal on the strap stretching device is provided in addition to that afforded by the usual plate or flange which extends between the strap ends and engages the edges of the seal at the sides of the strap. The present invention provides means whereby parts for support-

ing the seal are located both above and below the upper overlapping strap end and the slot through which this strap end extends may preferably be formed by providing a movable member for engaging the edge of the seal above the upper strap end. In the preferred embodiment, the supporting member which engages one edge of the seal is in the form of a pivoted gripping dog which is actuated to bear against the upper side of the strap so that it is normally in position to engage the edge of the seal during the stretching operation. This pivoted member is preferably actuated to move normally into engagement with the strap and it may readily be elevated from its normal position to permit the insertion of the strap beneath it.

Other features and objects of the invention relate to various details of construction and arrangement which will appear more fully hereinafter.

The nature of this invention will be understood from the following specification taken with the accompanying drawings in which one embodiment of the invention is illustrated. In the drawings,

Figure 1 shows a top plan view of the improved strap stretching device;

Fig. 2 is a perspective view of one form of a strap joint which may be employed for uniting the strap ends after the strap has been drawn taut by the use of the tool illustrated in Fig. 1;

Fig. 3 shows a side elevation of the strap stretching device illustrated in Fig. 1;

Fig. 4 shows a longitudinal section taken on the line 4—4 of Fig. 1;

Fig. 5 shows a side elevation of a portion of the device illustrated in Figs. 1 and 3 looking toward the side thereof opposite that shown in Fig. 3;

Fig. 6 shows a vertical section taken on the line 6—6 of Fig. 3;

Fig. 7 shows a sectional view taken on the line 7—7 of Fig. 4; and

Fig. 8 is a side elevation similar to that of a portion of Fig. 3 before the strap has been inserted beneath the gripping dog and with the operating lever in a position wherein the pawl thereby engages the teeth of the gear wheel which is employed to effect relative movement of the parts of the device during the strap stretching operation.

The invention is shown in the drawings as being employed in drawing a strap 10 taut around a box or package 11. The strap 10, which may be a flexible steel strap such as that ordinarily employed for reinforcing boxes or packages, has

one end portion 10a which is threaded through a metallic seal 12 in the form of a flat sleeve-like member. The extremity 10b of this portion of the strap is reversely bent about the seal 12 and 5 bears against the upper surface of the box or package 11. The other end portion 10c of the strap 10 also passes through the seal 12, the two portions of the strap being preferably threaded through the seal in overlapping relation before 10 the looped portion between the end portions of the strap is passed around the box or package. The purpose of the strap stretching device, which is designated generally by the numeral 13, is to draw the strap 10 taut around the package 11, 15 whereupon the seal 12 and the enclosed end portions of the strap are deformed to provide an interlocking joint. There are various forms of such interlocking joints which may be employed, the form illustrated in Fig. 2 being that disclosed 20 in the United States patent to Ralph H. Norton No. 1,260,016, dated March 19, 1918, according to which the seal 12 and the enclosed strap are sheared transversely at opposite edges to provide 25 opposed pairs of cuts 14 which permit the intervening metal to be deflected out of the plane of the seal and the strap ends to form lugs 15, thus providing abutting shoulders on the seal and the strap ends which prevent relative endwise movement of these connected parts.

30 The strap stretching device 13 comprises a head 16 carried at the end of a rack bar 17 and provided with a flange 16a which extends laterally from the head and between the end portions 10a and 10c of the strap, as best shown in Fig. 3. 35 This flange 16a is provided with a tapered end portion 16b which terminates in a thin edge 16c arranged to bear against the opposite edges 12a of the seal at opposite sides of the strap, thus holding the end portion 10a of the strap against 40 movement toward the right, as viewed in Fig. 3, during the strap stretching operation. The head 16 also carries a holding member or abutment 18 which is adapted to rest upon the upper side of the end portion 10c of the strap and which has a 45 flat transverse end face 18a adapted to bear against the transverse edge 12b of the seal between the lateral edge portions 12a which are engaged by the member 16a. The end portion 10c of the strap passes through the slot 19 between 50 the member 16 and the member 18. This slot is preferably formed by mounting the holding member or abutment 18 for relative movement with respect to the member 16 so that it may be moved toward and from the flange 16a to permit 55 the insertion of the strap beneath it. In the embodiment illustrated, the member 18 is in the form of a pivoted dog having a hub portion 18b which is mounted to pivot about a pin 20 passing through an aperture in the head 16 60 and provided with a transverse groove in its side for engagement by a holding pin 22 fixed in an aperture in the head, as shown in Fig. 4, to serve the double purpose of securing the pin 20 in place and also of securing the rack bar within the 65 head 16. The head 16 is provided with a flange 16d which overlies the holding member or abutment 18, and the parts 16d and the member 18 are provided with registering recesses to receive the ends of a coil spring 23 which normally 70 presses the member 18 downwardly into a position where it engages the upper side of the strap 10 in a location to abut against the end of the seal 12.

At certain times, and particularly when the 75 support of the tool on the box or package is lim-

ited, there is a tendency of the end portion 10c of the strap at the right of the seal, as viewed in Fig. 3, to move upwardly away from the flange 16a and to bear against the underside of the holding member 18 with a possibility that the 5 pressure may raise the member 18 to prevent it from maintaining its engagement with the end of the seal 12. To overcome this possibility, the underside of the member 18 is concaved upwardly between its ends as shown at 18c so that the strap 10 may bow upwardly without exerting substantial 10 pressure on the member 18 tending to tilt it upwardly. In addition, the hub portion of the member 18 is provided with a projection or shoulder 18d forming a lever arm extending 15 downwardly toward the strap at the right of a vertical plane passing through the axis of the pin 20, so that if the strap does bow upwardly, it will press against this projection 18d and thus apply to the member 18 a force opposing any 20 tendency of the extremity 18a thereof to move upwardly out of engagement with the seal.

The end portion 10c of the strap extends over the upper surface of the flange 16a and over another flange 24a which projects forwardly from 25 a frame or housing 24 having a passage of rectangular cross section therethrough which is slidably fitted by the rack bar 17. This housing 24 is provided with an upwardly extending arm 24b provided with a handle 25 which may be 30 engaged by one hand of the operator during the manipulation of the tool. The housing 24 is also provided with another forwardly extending flange 24c, located somewhat below the plane of the body portion of the housing, as shown in Fig. 3, 35 which is intended to rest upon the upper side of the strap 10 above the package, in the event that the box or package is large enough to support the housing 24 at this point. The end portion 10c of the strap is held in fixed relation to the housing 40 40 by a gripping dog 26 which is pivotally mounted upon a pin 27 extending through the housing 24, the head of the pin overlapping the gripping dog and the rear extremity thereof being engaged by a cotter pin 28, as shown in Fig. 45 5, for preventing its accidental removal. The housing 24 is provided with a boss or flange 24d which overlies the gripping dog 26 and which has an arcuate surface 24e forming a bearing for the correspondingly curved surface of the upper 50 end of the gripping dog, thus relieving the strain upon the pin 27 when tension is put upon the strap 10. The gripping dog 26 is inclined downwardly and toward the right, as viewed in Figs. 3 and 8, and it is provided at its lower end with 55 a gripping surface 26a adapted to engage the upper surface of the end portion 10a of the strap above the flange 24a of the housing. This gripping dog is normally forced into engagement with the strap on the flange 24a by a coil spring 29 60 which engages registering recesses in the upper inclined face of the gripping dog and in a shoulder 24f formed on the housing 24.

In order to effect relative movement of the gripping dog 26 and the flange 24a with respect 65 to the extremity of the strap which is held by the seal 12 in fixed relation to the flange 16a and the member 18, the housing 24 is capable of being moved bodily along the rack bar 17, and this movement is effected through the actuation of a 70 gear wheel 30 which has teeth 30a meshing with the rack teeth 17a formed on the upper side of the rack bar, as shown in Fig. 4. This gear wheel 30 is mounted to revolve about a pin or axle 31 having a head 31a at one end provided with a 75

- flat side which bears against one flat edge of the previously described shoulder 24, as shown in Fig. 8. At its other end, the pin 31 is threaded for engagement by a nut 32, shown in Fig. 1.
- 5 The gear wheel 30 is mounted between the flanges 33a formed at the lower end of an operating lever 33 which carries a ball or handle 34 at its outer end. The flanges 33a of this lever are apertured for pivotal engagement with the pin 31 and when 10 the lever 33 is rocked in the appropriate direction by the pin 31, the gear wheel 30 is adapted to be rotated through the agency of a pawl 35 which is pivotally mounted in the flanges 33a and which is provided between these flanges with 15 a portion 35a of semicircular cross section, the edges of which constitute teeth, one of which is adapted to enter the spaces between the teeth 30a of the gear wheel. When this tooth engages a space between the gear teeth, as shown in Fig. 20, movement of the lever 33 toward the right, as viewed in that figure, will rotate the gear wheel 30 in the proper direction to move the housing 24 and the gripping dog 26 toward the right, as viewed in Figs. 3 and 4, thus drawing the strap 25 taut.
- The pawl 35 is normally rotated in a direction to cause its tooth to engage the gear teeth by a coil spring 36 which surrounds the projecting reduced end of the pawl 35 at the rear side of 30 the lever 33, one end of the spring passing through a transverse aperture in the end of the pawl and the other end of the spring engaging a lug 33b which is formed on the side of the lever, as shown in Fig. 5. The lever 33 may be given a reciprocating movement in order to rotate the gear wheel 30 by successive increments, and during each movement of the lever 33 toward the left, as viewed in Fig. 4, the flat face of the 35 semicircular portion 35a of the pawl will pass over the outer ends of the teeth 30a. During each reverse movement of the lever 33, the gear wheel 30 is held against reverse rotation by one of two similar detents 37 which are arranged side by side and pivotally mounted between the side 40 walls of the housing upon the pin 27 which carries the gripping dog 26. Each detent has a tooth 37a adapted to enter between two of the teeth 30a of the gear wheel and it also has an angularly disposed arm 37b extending upwardly 45 at the left of the lever 33, as viewed in Fig. 4. A coil spring 38 is mounted between the arm 37b of each detent and the end wall 24g of the housing, each spring having its ends mounted in registering recesses in these opposed parts. The 50 detents are thus forced into normal engagement with the teeth of the gear wheel 30. The arm of one detent which carries its tooth 37a is longer than the corresponding arm of the other detent so that they are adapted to engage alternate 55 teeth of the gear wheel to prevent reverse rotation thereof, this arrangement being adapted to cause the gear wheel to be held regardless of the precise position it occupies when released by the pawl 35.
- 60 Upon extreme movement of the lever 33 toward the left, as viewed in Figs. 3 and 4, both detents 37 are adapted to be released from the gear wheel 30 due to the engagement with the arms 37b of the lower end face 33c of the lever just above 65 the flanges 33a which causes the detents to be rocked about their pivot against the compression of the springs 38. The pawl 35 may also be released from its engagement with the gear wheel 30, at the time of releasing the detents 37 therefrom, in order to allow a free rotation of the 70 gear wheel 30 and a consequent free movement of the housing or frame 24 on the rack bar 17. This release is effected by the engagement of the flat surface 35c on the projecting end of the pawl with a shoulder 24h formed on the frame 24 above the pivot pin 31, as shown in Figs. 3 and 8. As the lever 33 is moved toward the left from the position shown in Fig. 8, the flat surface 35c rides over the shoulder 24h, thus turning the pawl so that its tooth passes out of engagement 10 with the teeth of the gear wheel. As the motion of the lever toward the left continues, the flat face 35c occupies a position parallel to and in proximity to the upper flat face 24i of the side wall of the housing, as shown in Fig. 3, thus 15 holding the pawl positively out of engagement with the teeth of the gear wheel. When the parts are in the relative position shown in Fig. 3, the housing or frame 24 may be moved freely on the rack bar 17 through the agency of the handle 25 20 in order to locate the gripping dog 26 in the desired position for engagement with the upper end portion 10c of the strap. When the gripping dog 26 has been properly positioned and the strap is held thereby against the shoulder 24h 25 of the frame or housing 24, the parts are in readiness for drawing the strap taut and upon movement of the lever 33 toward the right, as viewed in Fig. 3, it will reach a position where the pawl is released by the shoulder 24h so that the spring 30 30 will then restore the pawl into engagement with the teeth of the gear wheel, thus permitting continued movement of the lever in the same direction to effect rotation of the gear wheel and a consequent movement of the frame 24 on the 35 rack bar 17 with a resulting stretching of the strap so that it is drawn taut around the package. Of course, this tightening of the strap may be effected by several reciprocating motions of the lever 33 without causing the pawl to be released by the engagement of its surface 35a with the shoulder 24h. During this operation, the end 10a of the strap is held by engagement of the flange 16b with the sides of the seal and also by the engagement of the lower part of the flat end 45 face of the holding member 18 with the upper transverse edge of the seal, so that the strap may be drawn taut to any desired degree without injuring the seal 12 or interfering with its use in the formation of an interlocking joint, such as 50 that shown in Fig. 2.
- When the joint has been formed, the stretching device may be released from the strap and this is preferably done after cutting off the strap adjacent the seal 12, which may be done through 55 the agency of the holding member 18 when this member is provided with an end face adapted to effect the shearing of the strap adjacent the seal, as described and claimed in the copending application of Charles G. Heslet and Edwin C. Lay- 60 man, Serial No. 288,694, filed August 7, 1939.
- Although one form of the invention has been shown and described by way of illustration, it will be understood that it may be constructed in various other forms coming within the scope of 65 the appended claims.
- I claim:
1. The combination in a strap stretching device, of a member adapted to extend between two overlapping ends of a strap passed around 70 a package and to bear against one end of a seal surrounding said strap ends and attached to one of them, a second member movably mounted on said first named member and adapted to bear against said end of said seal on the side of one 75

of said strap ends opposite said first named member, means for gripping the end of the strap which is not attached to said seal, and means for effecting relative movement of said gripping means and said members to draw the strap taut around the package.

5. The combination in a strap stretching device, of a member adapted to extend between two overlapping ends of a strap passed around 10 a package and to bear against one end of a seal surrounding said strap ends and attached to one of them, a second member movably mounted on said first named member and adapted to bear against said end of said seal on the side of one 15 of said strap ends opposite said first named member, means tending to move said second named member into engagement with said strap, means for gripping the end of the strap which is not attached to said seal, and means for effecting relative movement of said gripping means and said members to draw the strap taut around the package.

6. The combination in a strap stretching device, of a member adapted to extend between 20 two overlapping ends of a strap passed around a package and to bear against one end of a seal surrounding said strap ends and attached to one of them, a second member pivotally mounted on said first named member and adapted to bear against said end of said seal on the side of one 25 of said strap ends opposite said first named member, said pivoted member extending longitudinally from its pivot toward said seal and being concaved on the side thereof toward said strap, said pivoted member also having a projecting arm adapted when engaged by said strap to force the free end of said pivoted member into engagement with said strap, means for gripping the end of the strap which is not attached to said seal, and means for effecting relative movement of said gripping means and said members to draw the strap taut around the package.

7. The combination in a strap stretching device, of a member adapted to extend between two overlapping ends of a strap passed around a 30 package and to bear against one end of a seal surrounding said strap ends and attached to one of them, a second member pivotally mounted on said first named member and adapted to bear against said end of said seal on the side of one 35 of said strap ends opposite said first named member, means for gripping the end of the strap which is not attached to said seal, and means for effecting relative movement of said gripping means and said members to draw the strap taut around the package.

8. The combination in a strap stretching device, of a head having a laterally extending flange adapted to extend between two overlapping ends of a strap passed around a package and to bear against the edges of a seal surrounding said strap ends and attached to one of them, a holding member pivotally mounted on said head and extending longitudinally over the upper strap end to engage the transverse edge of said seal on the 35 side of said upper strap end opposite said flange, a gripping device adapted to engage the portion of said strap which is not attached to said seal, and means for effecting relative movement of said gripping device and said head for drawing the 40 strap taut around the package.

9. The combination in a strap stretching device, of a head having a laterally extending flange adapted to extend between two overlapping ends of a strap adjacent a tubular seal surrounding said strap ends and attached to the lower one of them, said flange being adapted to bear against the edges of said seal at the sides of said strap ends, a holding member pivoted on said head and having a transverse face adapted to bear against the transverse edge of said seal on the upper side of the upper strap end, a spring tending normally to move said holding member into engagement with the upper strap end, a rack bar attached to said head, a frame slidably mounted on said rack bar, a gripping device carried by said frame for holding the upper end of said strap, and means carried by said frame and cooperating with said rack bar for effecting relative movement of said frame and said head to draw the 50 strap taut around the package.

FREDERICK A. ENDRESS.
